UNITED STATES PATENT OFFICE

112,634

DESIGN FOR A LIGHTING FIXTURE

George C. Devol, Jr., St. Albans, N. Y., assignor to United Cinephone Corporation, Long Island
City, N. Y., a corporation of New York

Application August 13, 1938, Serial No. 79,315

Term of patent 7 years

To all whom it may concern:

Be it known that I, George C. Devol, Jr., a citizen of the United States, residing at St. Albans, Long Island, in the county of Queens and State of New York, and whose post-office address is % United Cinephone Corporation, 43-47 33rd Street at Queens Blvd., Long Island City, New York, have invented a new, original, and ornamental Design for a Lighting Fixture, of which the following is a specification, reference being had to the accompanying drawing, forming part thereof.

What is claimed:

The ornamental design for a lighting fixture, substantially as shown.

GEORGE C. DEVOL, JR.
